Earl L. Canfield, Book Hill Road, Essex, Conn.

Continuation of design applications Ser. No. 80,386
and Ser. No. 80,408, June 15, 1964. This application
July 15, 1965, Ser. No. 86,443

Term of patent 14 years

(Cl. D48—20)

FIG. 1 is a top plan view of a desk lamp or similar article, showing my new design wherein the base is similar in shape to that base shown in FIG. 3, but proportionately smaller in scale.

FIG. 2 is a side elevation thereof.

FIG. 3 is a top plan view of a modification of a desk lamp or similar article showing my new design.

FIG. 4 is a side elevation of the modification shown in FIG. 3.

This application is a continuation of design application Serial Numbers D. 80,386, filed June 15, 1964, and D. 80,408, filed June 15, 1964, and now abandoned.

I claim:

The ornamental design for a desk lamp or similar article, as shown and described.
